CLAIM

The ornamental design for set of boxes with packaging, as shown and described.

DESCRIPTION

FIG. 1 is a perspective view of a set of boxes with packaging, showing the design;

FIG. 2 is an exploded view of FIG. 1;

FIG. 3 is a side bottom assembled view of a portion of FIG. 1;

FIG. 4 is a top view of a portion of FIG. 1;

FIG. 5 is a top assembled view of a set of boxes with packaging;

FIG. 6 is a side perspective view of FIG. 5;

FIG. 7 is a bottom assembled view of FIG. 6;

FIG. 8 is a side perspective view of FIG. 6;

FIG. 9 is an exploded view of FIG. 8;

FIG. 10 is a side view of FIG. 6; and,

FIG. 11 is an opposite view of FIG. 6.

(Continued)

The broken line portion of FIG. 2 is included to show environment that forms no part of the claim design. The dash-dot lines of FIGS. 1, 2, 3, and 8-11 represent unclaimed perforation lines.

1 Claim, 4 Drawing Sheets
